EX
OR D 16,079

DESIGN.

—o—
E. BENNETT.

PITCHER.

No. 16,079.

Patented May 12, 1885.

UNITED STATES PATENT OFFICE.

EDWIN BENNETT, OF BALTIMORE, MARYLAND.

DESIGN FOR A PITCHER.

SPECIFICATION forming part of Design No. 16,079, dated May 12, 1885.

Application filed March 28, 1885. Term of patent 7 years.

To all whom it may concern:

Be it known that I, EDWIN BENNETT, a citizen of the United States, residing at Baltimore city and State of Maryland, have invented 5 and produced a new and original Design for Pitchers, of which the following is a specification, reference being had to the accompanying photographic illustration, forming part thereof.

10 The photograph represents a perspective view of the newly-designed pitcher.

The pitcher is formed with the representation of a reptile at its neck, one half of which reptile is disposed on one side of the neck and the 15 other half on the other side, while the mouth of the reptile forms the mouth of the pitcher, and the tail of the reptile is turned down to form the handle of the pitcher. The surface of the pitcher is subdivided by grooves into 20 aliquot hexagonal subdivisions.

The leading feature of the design is the representation of the reptile at the neck of the pitcher, with its mouth forming the pitcher's mouth and with its tail forming the pitcher's 25 handle.

What I claim is—

1. The design for a pitcher herein shown and described, the same consisting of the reptile at the neck of the pitcher, having half its body on each side of the said neck, and having 30 its mouth disposed to form the mouth of the pitcher, and its tail bent down to contact with the body of the pitcher and disposed to form the handle.

2. The design for a pitcher herein shown 35 and described, the same consisting of the reptile at the neck of the pitcher, having half of its body on each side of said neck, and having its mouth disposed to form the mouth of the pitcher and its tail disposed to form the handle, the body of the pitcher being swelled to 40 a greater diameter than the base and provided with aliquot hexagonal subdivisions on its surface.

EDWIN BENNETT.
